VARIABLE DELIVERY PUMP OR MOTOR

Elek K. Benedek, Mount Gilead, Ohio, assignor
to The Hydraulic Press Manufacturing Company, Mount Gilead, Ohio

Application January 29, 1932, Serial No. 589,746

5 Claims. (Cl. 103—161)

This invention relates to rotary radial pumps or motors in which rotors revoluble about parallel axes are positively connected through piston and cylinder assemblies to cause drive of one rotor by the other through such connections.

5 Pumps of the type referred to include primary and secondary rotors rotatable about parallel axes and shiftable relatively to vary the relative eccentricity of one to the other for varying the output of the pump. Radial piston and cylinder assemblies are the connections between the rotors to engage the rotors for synchronous rotation. Loose connections even though slight, are sufficient to upset perfect dynamic balance of the rotating parts and cause dynamic vibrations, noise, unnecessary wear and breakage.

10 It is the purpose of my invention to provide a balanced pump operating at high speed and high pressure, in which a primary and a secondary rotor are connected and balanced by novel means, to provide for maximum load carrying capacity through well lubricated bearing surfaces, and one which effectively eliminates friction due to misalignment, and all loose connections which produce impact, or phase differences under conditions of operation. Another object of the invention is to provide a novel integral piston and cross head unit in which the cross head is equipped with adjustable means to permit, in 15 assembly, self alignments of the units without undue operative play; and in which means is provided for directing the hydraulic piston and reaction load forces to a single focal point.

20 Another object of the invention is to provide means in combination with the cross heads in which the load transmitting surfaces are so formed as to provide high pressure wedge shape oil films at all times between said means and reaction surfaces.

25 Another object of the invention is to provide novel means to balance the synchronously rotating primary and secondary rotors, especially when the pump is set at the maximum stroke and the rotating masses are in eccentric relation, thereby to improve the performance and life of the pump.

30 Other objects will in part be obvious and in part be pointed out hereinafter.

35 To the attainment of the aforesaid objects and ends, the invention still further resides in the novel details of construction, the combination and arrangement of parts, all of which will be first 40 fully described in the following detailed description, then be particularly pointed out in the ap-

pended claims, reference being had to the accompanying drawings, in which:—

Figure 1 is a vertical cross section of the pump taken through the main meridian plane of the pistons, part being shown in elevation and part 5 in section.

Figure 2 is a horizontal section taken through the axis of the pump, parts being shown in section and in elevation.

Figure 3 is a detail fragmentary vertical cross section taken through the axis of one cylinder and piston assembly and illustrates the self-aligning quality of the cross head when the reaction member is out of alignment.

Figure 4 is a detail fragmentary vertical longitudinal section taken through the axis of one cylinder and piston assembly and shows a slightly modified form of cross head in which the adjustable surfaces of the cross head constitute a portion of a spherical surface with the center 15 line on the axis of the cylinder barrel and serve to direct hydraulic reaction forces to a focal point in the centerline of the pistons.

Figures 5, 6, and 7 illustrate the outer element of the two-piece cross head shown in Figure 3 20 in central longitudinal section, in plan and in central transverse section respectively.

Figures 8, 9, and 10 illustrate the adjustable element of the cross head shown in Figure 4 25 in central longitudinal section, in plan and in central transverse section respectively.

Figure 11 is a diagrammatic detail view illustrating a piston unit of a well known conventional form of pump in which the load is carried on a 30 wrist pin carried by slippers and which are subject to wear as diagrammatically illustrated in Figure 11a.

Figure 12 is a view similar to Figure 11 showing another well known conventional form of 35 piston unit wherein the load is carried on a miniature push pin.

Figure 13 is a comparative view similar to Figures 11 and 12 and illustrates my improved piston unit in a manner permitting a comparison 40 of the load transmitting means with the conventional units mentioned in regard to friction and construction.

Figure 14 is a diagrammatic cross sectional view illustrating the non-synchronous action 45 which can take place when the primary and secondary rotors are connected by flexible devices such as are illustrated in Figure 12.

Figure 15 is a comparative view similar to Figure 14 and shows the effect of employing 50

rigid piston units of the type shown in Figures 3 and 4.

Figure 16 is a diagrammatic cross section illustrating the relative positions of a piston unit and rotors in seven successive positions during one revolution of my improved pump structure.

Figure 17 is a cross section illustrating the relative positions of primary rotor and a radial series of seven pistons.

10 Figure 18 is a diagrammatic view of the secondary rotor and illustrates relative positions of secondary rotor and a radial series of seven pistons.

15 Figure 19 is a composition of Figures 17 and 18 and illustrates the relative position of the piston units and both the primary and secondary rotors.

20 Figure 20 is a detail vertical cross section taken on the line 20-20 on Figure 2.

25 Figure 21 is a detail perspective view of the control rods and assembled bearing rings of the secondary rotor.

20 Figure 22 is a detail sectional view of a cross head and discloses means for limiting the adjustment of the associated parts.

30 In a practical embodiment of the invention I provide a pump casing comprising a cylindrical ring 5 having integral supporting feet 6, and upper and lower parallel guide pads 7. The cylindrical casing is also provided with diametrical control hubs in which shifter rod bores 8 are formed, and provided with drain back ducts 9 which communicate the interior of the casing to enable fluid to leak past the control rods.

35 The cylindrical cover is completed by end casings 10 and 11, which are centered on shoulders 12 in regard to casing ring 5 and which are flanged and secured as at 13 to the respective ends of the casing ring. Each end cover is also provided 40 with an annular recess 14 adapted to receive a sealing and bearing ring 15. As will be observed by reference to Figure 2 the rings 15 are apertured to receive and enable them to slide axially on screws 16 secured in the end covers. In the 45 space between each ring 15 and the adjacent end cover recess wall, spring elements 17 are interposed and serve to hold the rings toward the rotors to close the pump chambers formed within the casing ring 5 and end covers 10 and 11.

50 The end cover 10 is provided with an axial bore 18 in which the enlarged head 19 of the cylindrical pindle 20 is rigidly secured and positioned by means of a key 21. The end cover 10 is provided with diametrically opposed intake and exhaust ports 22 and 23 respectively which lead into the bore 18 and register with ports 24 and 25 formed in the enlarged head of the pindle. See Figures 1, 2, and 20.

55 The pindle port 24 communicates with a pair of longitudinal ducts 26 provided in the pindle, and the port 25 communicates with a similar pair of ducts 27 formed in the pindle. The pairs of ducts 26 and 27 extend only part way through the pindle and have their outer ends plugged as 60 at 28 so that communication with said ducts through the pindle head may be had only through the ports 22-25. It is understood that each of the pairs of ducts 26 and 27 are intake and exhaust ducts respectively, according to the adjustment of the pump during the particular interval.

65 At their ends opposite the plugs 28 the upper and lower pairs of ducts 26 and 27 communicate with upper and lower pindle ports 29 and 30 respectively, which afford communication between

the respective pairs of ducts and the cylinder portion ports in a manner which will become apparent as the description progresses. The metal remaining after the forming of the ports 29 and 30 results in the provision of two solid bridge pieces 31, which are so constructed and arranged that the center line of these bridge pieces always is parallel with the direction of shifting, or in other words, the line on which the control rods move in varying the output of the pump always coincides with the center line of the bridge pieces.

70 The end cover 11 is axially bored and is counterbored to receive a bearing sleeve 40. The bearing sleeve 40 forms a plain film bearing for the head 41 of a drive shaft 42 which extends from the casing through a packing gland 43 for attachment with suitable driving means not shown. The gland bearing 44 is flange-secured to the end bell 11.

75 A cylinder barrel or primary rotor 45 is rotatably mounted in the pump casing, having its principal bearing, a plain oil film bearing, on the main cylindrical body portion 20 of the pindle. The primary rotor is engaged at its ends by the sealing and bearing rings 15 which are pressed slightly against the end faces thereof by the spring elements 17.

80 The primary rotor 45 is provided, in its central transverse plane, with a plurality of radial cylinder bores 46 spaced equidistantly and open radially. At their inner ends the cylinder bores 46 communicate, through ports 47, with the pindle and the ports 29 and 30. Thus, as the primary rotor is rotated about the pindle each cylinder bore 46 thereof will communicate alternately with the pindle cut-outs 29 and 30 and the upper and lower pairs of ducts 26 and 27 respectively.

85 At its closed end the primary rotor is provided with a cross groove, and the drive shaft head 41 is provided with a similar cross groove lying in a plane normal to the plane of the rotor groove, and these grooves are adapted to receive correspondingly positioned coupling ribs extending from the opposite faces of the coupling head 51 which is interposed between the cylinder barrel 45 and the shaft head 41 and which is disclosed in detail in my copending application No. 564,404.

90 A pair of shifter rings 54 are mounted within the pump casing and are rigidly connected and held in the spaced relation shown in Figure 2 by yokes 55 one thereof being provided at each side of the secondary rotor, and each including spacer shoulders 56. The yokes 55 are secured by screws 57 or otherwise to the rings 54 and to these yokes the shifter rods 58 reciprocable in the guides 8 are secured in any approved manner as indicated at 95 59. Each ring 54 is provided with a pair of slide guide pads 60 which engage the pump casing pads 7 and control shifting movement of the rings so that their axes and the axis of the secondary 100 rotor having rotary bearing therein always align and lie in the line of the axis of the pindle and center line of the bridge portion 31. The yokes 55 have their outer surfaces curved to accord in shape with the surfaces of the casing ring 5 which they oppose so as to adapt them to use as limiting stops.

105 The numeral 61 designates the surface of the ring or bearing member 54 on which is formed a high pressure lubricant film as disclosed in my copending application for patent filed August 18, 1931, Serial No. 557,888.

110 Surrounding the primary rotor 45 is an eccentric or secondary rotor 62, the center of rotation

of which is adjustable relative to the axis of the primary rotor by means of the shifter rings 54. The secondary rotor 62 surrounds the primary rotor 45. The secondary rotor comprises a ring 5 having a deep circumferential channel 65 comprising successive tangential sections and having radial walls or flanges 64. Within this channel move piston heads 76-77 of the connecting assemblies, the stems or bodies 74 of the pistons extending through elongated perforations or openings 68. To adequately assure retention of ample bath of lubricant, a lubricant retaining ring 66 is secured in place by screws 67 or the like to completely close or seal the channel 65 in a radially outward direction. It will be observed by reference to Figures 1 and 2 that the annular recess 65 communicates with the interior of the secondary rotor 62 through elongated openings 68, one of which is provided for each cylinder bore 20 provided in the cylinder barrel 45.

The provision of the central shoulder enlargement on the secondary rotor 62 provides lateral bearing hubs or flanges 69 which may be equipped with bearing rings 70 in cooperation with the oil film bearings 61. The secondary rotor also has lateral engagement with the bearing and sealing rings 15 for the purpose of retaining lubricant as hereinbefore described. The hubs are apertured as at 71 so that free passage of lubricating fluid to the oil film bearings 61 is provided for.

It will be observed by reference to Figures 1 and 2 that the secondary rotor 62 is provided, between the flanges thereof which define the tangential recess 65, with a plurality of pairs 35 of tangentially disposed reaction plate receiving grooves 72 and similar pairs of radially disposed reaction plate locking grooves 73 which open to the periphery of said rotor.

Pistons 74 are reciprocable in the bores 46 and 40 extend through the openings 68 formed in the secondary rotor 62. Each of the pistons has an integral cross-head 75 which, together with the block 76, constitutes a piston cross head unit.

In the form of the invention shown in Figures 45 1, 2, 3, 5, 6, and 7, the outer face 77 of each piston T-head is in the nature of a convex surface that is cylindrical transversely and arcuate or convex throughout its length, the centers of curvature lying on an axis perpendicular to the axis of the piston, this axis preferably coinciding with the pintle axis. The mating face 78 of the block 76 is shaped in the form of a concave surface in suitable manner so as to engage the cross-head face throughout the whole area. By 55 reason of this geometry the reaction forces acting on the piston cross heads are, in every position thereof, directed to a focal point in the axis of the piston of the particular unit and in the intersection with the axis of the pintle or primary rotor.

The intersection of the pintle axis with the main meridian of the pistons might be termed as the focal point in the pump. I find it advantageous to arrange the curved mating surfaces of 65 the cross head elements 75 and 76 so that the common center of curvature of all of the cross heads will coincide with the pintle axis at all relative positions.

In Figures 4, 8, 9, and 10, I have disclosed a 70 modified form of cross head element engaging surfaces in which the mating faces 77^a and 78^a form a part of a spherical surface having its center of curvature lying in the radial or axis of the respective piston and in the intersection point 75 with the pintle axis. These surfaces concentrate

or direct the load forces to a focal point lying in the piston axis as above outlined.

The upper or outer face of each cross head element 76 engages a stationary reaction plate 80 having lateral tenons 81 extending into the tangential grooves 72 provided therefor between the flanges of the secondary rotor and each such plate is provided with a threaded tap to receive the screw 82 by which a lock plate 83 having its ends extended into the radial grooves 73 of said ring or eccentric is secured to position upon said reaction plate. By reason of the extension of the ends of the locking plates into the radial grooves 73, they serve to secure the reaction plates against tangential movement relative to the crosshead 15 elements 75, 76. The tenons 81 serve to hold the reaction plates against radial movement and thus enable them to take up the radial thrusts of the pistons 74.

The casing ring 5 may be provided with a 20 drain 84, if desired, so that fluid leaking into the pump chamber surrounding the shifter rings 54 may be drained from the pump casing.

It will be understood that with the pump parts positioned as illustrated in Figure 1 of the drawings, with the shifter ring center coinciding with the axis of the pintle, the primary rotor 45, the secondary rotor or eccentric 62 and connected parts will rotate freely within the casing without effecting any pumping action. In other words, 30 Figure 1 illustrates a neutral position of the pump.

By means of the shifter rods 58 and yokes 55 the shifter rings 54 may be shifted so that the center line of the eccentric 62 will be moved to 35 one side or the other of the center line or axis of the pintle 20. Let us assume that the ring is shifted to the right in Figure 1, and that the direction of rotation of the cylinder barrel 45 is clockwise. In this position of the parts all 40 of the pistons above the center line will be moved radially outward and will suck fluid through the intake port 22 and the upper pair of ducts 26, and the pistons below the center line will be moved radially inward and will expel fluid 45 through the lower pair of ducts 27 and the exhaust port 23.

Obviously, when the eccentric 62 is shifted toward the left of the center line of axis of the pintle the cycle will be reversed and the pistons 50 above the center line will expel fluid while those below the center line will draw fluid into the cylinder bores.

It will be understood that whenever the eccentric 62 is adjusted off center and the primary 55 rotor 45 is rotating, the pistons 74 will be reciprocated radially in their receiving bores, the cross heads 75, 76 oscillating tangentially in the secondary rotor recess 65 because of the off center relation of the secondary rotor.

The cross heads shown in Figures 3 and 4 are made as large as possible so that the multi-dimensional mating reaction surfaces of the component parts thereof are of maximum area, thereby to minimize the unit pressure per unit 65 area and consequently reduce to a minimum wear and piston knock.

As hereinbefore stated the mating surfaces of the cross head elements 75 and 76, as shown in Figures 1, 3, 5, 6, and 7, form part of a cylinder surface having its center lying in the radial or axis of all the pistons and or in the centerline of the primary rotor, whereas in Figures 4, 8, 9, and 10 these surfaces form a part of a sphere having its center in the same point. Thus the 75

mating surface of the cross head elements 75 and 76 preferably form part of a cylinder or of a sphere respectively, with their centers of curvature always lying in the axis or radial of the respective piston unit and as close to the pintle axis as operation will permit.

In order to obtain maximum cross head strength and to properly direct reaction forces, I prefer to make the cross head surfaces 77 convex. But they may be of any other form which will concentrate the reaction forces in a focal point lying in the centerline of the cylinders.

Whenever the receiving grooveways 65 are formed with error so that a rigid cross head element could not accurately bear against the reaction face of the plate 80, my improved solid adjustable cross head will act automatically to compensate for this error and assure the desired full surface contact between cross head and reaction plate.

In Figure 3 I have shown how the novel cross head unit self-aligns under conditions above outlined. The element 76 has only to shift to the right or to the left as indicated in order to permit the reaction faces of 76 and 80 to fully engage. This tangential self-alignment is usually satisfactory for pumps wherein a single row or only a few rows of pistons have been used. However, in a multi-row pump design, where an axial deflection of the secondary rotor is unavoidable, a lateral self-alignment is desirable and it is for such large pump design, that a lateral self-alignment is provided for as shown in Figure 4, wherein a spherical surface form of cross head surface is disclosed. See also Figures 8, 9, and 10.

While I have disclosed simple spherical and cylindrical surfaces, I wish it to be understood that the scope of my invention embraces such other surfaces, other than above said surfaces, 40 which are capable of like self-aligning and load carrying functions.

By reason of their cooperative curved surfaces the cross head elements 75 and 76 in effect constitute a single cross head block and act as one piece except for the relative adjustment for self-aligning purposes. Therefore, the element 76 follows the harmonic oscillation of the piston cross head unit 75 and there is no clearance between the cooperative surfaces 77 and 78 except that which is sufficient to accommodate a thin film of oil which prevents wear of the cooperative surfaces and prevents noise at the pressure change of the piston, especially in the dead centers as the piston changes from suction to delivery stroke or vice versa.

In those critical moments, as it is well known, at high speeds, there are 30 to 50 strokes for each piston per second, or the time for a whole stroke of the piston is about 1/30-1/50 of a second. By further considering the fact that the pressure change on the piston must be only a small fraction of the whole stroke period, it will be evident that the time of such pressure change, by assuming it to be 1/1000 of the full stroke time, will figure in absolute time measure to 1/29000 of one second. It will be practical to say that the pressure change in the dead centers in high speed, high pressure, rotary pumps of commercial design, considering that medium sized pumps have to run at a speed more than 860 R. P. M., is approximately 1/30000 (one thirty-thousandth) of one second. It is therefore evident that any slack in the cross head connection must be taken up in an almost infinitesimal time element, that is, with a blow.

In my novel piston construction, the large contact surface in cooperation with a thin oil film eliminates that high frequency noise caused by the take-up of loose cross head connection in the pressure change points of the stroke. It is furthermore evident from Figure 3 and Figure 4 that the cooperative surfaces 77, 78 or 77^a, 78^a of the cross head, being curved surfaces prevent the tangential escape of oil in the case of the cylindrical surfaces or prevent the escape in all 10 directions in the case of the spherical surfaces. Therefore, in my novel type of pump, provision is made to oil-cushion the piston load in the moment of pressure change and provide a resultant dashpot effect assuring quiet operation of 15 pump. It is obvious that such dashpot effect cannot occur between plain ordinary surfaces where the oil film can be squeezed out at low pressures.

It will be observed by reference to Figures 1, 5, 20 6, and 7 that the cross heads each include inner plane faces 85 opposed to the outer working faces of the secondary rotor tangential grooveways and that the reaction faces of the elements 76 there- 25 of, opposed to the reaction faces of the plates 80 are provided with a plurality of pairs of inclined plane faces 86 opposedly inclined in the direction of reciprocation of the cross heads. At the meeting edges of each pair of such faces a trans- 30 verse oil groove 87 is formed as a supply channel 30 for oil.

The shell 66 retains oil thrown into the secondary rotor chamber 65 so that the cross heads always reciprocate in an oil bath, the surfaces 86 serving during reciprocation to build up very 35 efficient high pressure oil film bearings. Thus the provision of the retaining shell, the inclined surfaces 86 and the grooves 87 provide for highly efficient lubrication and great load carrying capacity. In application, the slant faced surfaces 40 are interchangeable and the film bearings afforded thereby serve to eliminate friction and impacts and assist in assuring synchronous rotation of the primary and secondary rotors.

As outlined above the curved surface engage- 45 ment normally assures against displacement of the cross head elements 75 and 76. However, should long usage occasion wear resulting in inefficiency in this respect, this condition can be guarded against by provision of a ball key 88 seating in a hemispherical seat 89 in the element 75 and received in a slightly enlarged recess 90 in element 76 so that self-aligning movement of 76 on 75 will be permitted but greater displacement of these parts positively limited. See Fig- 55 ure 22.

In Figure 16, A indicates the rotating primary rotor; B the eccentric or secondary rotor; and C the piston units which serve as rigid coupling elements connecting the primary and 60 secondary rotors. This diagrammatically illustrated radial tangential movement kinematic is capable of functioning at high speed and high pressure without impact and knocking if the connection of the primary and secondary rotors A 65 and B is rigid. This desirable condition can be satisfied only when the radial path of the piston plunger is at a right angle to the tangential path of the cross head at all times or at all phase angles ϕ . This is equivalent to requiring that 70 the plunger be parallel with the momentary center-line O₂ 2 of the tangential cross head path. By observing the geometrical relation at the right hand side of Figure 16 as $\phi=0$, it will be seen that the center line O₁ 1 of the primary 75

5 rotor coincides with the center line of the secondary rotor O_2 at this instant. From this instant, however, following an anti-clockwise rotation of the assembly as shown by the arrow, the center line of the primary rotor will take the lead, the distance of lead being proportional with the trigonometrical sine of the angle ϕ , that is it is equal to $\rho s \sin \phi$, where ρ is the eccentricity of the secondary rotor.

10 By following further the rotation of the assembly unit to an angle larger than 90° , there is still a relative position of the center lines of the primary and secondary rotors and the center line of the primary rotor still is in a leading position. At 15 180° however the center lines coincide or merge again. After 180° , however, the secondary rotor "B" or eccentric takes the lead, and this relative condition continues the remainder of the 360° of travel or to 0° degree.

20 At zero degree, there is a change again, i. e. the center line of the primary rotor "A" will again assume the leading position. In an assembly where the center O_2 of rotation of the secondary rotor "B" is to the right of the center O_1 of rotation of primary rotor "A", the rotation being anti-clockwise as indicated in Figure 16, the piston center line will have a motion so related to the center line of the secondary rotor that it will be in a leading position from 0° to 180° and thereafter in a follow up position from 180° to 360° . During all of these positions the two center lines must be absolutely parallel in order to limit the relative positions. At the instances of 0° and 180° the center lines cross each other, and the one 35 will go over to a relatively accelerated motion in regard to the other.

With the above in mind it should be apparent that if at either point of change where the two center lines have to cross each other as above outlined, one of the rotors is not in the proper geometrical relation due to flexible coordination of the parts of the assembly (see for example Figure 40 12 and Figure 14, where the primary rotor is in a phase lag of an angle $d\phi$ in relation to the driving rotor "B") and the lagging element must overcome the lag and as indicated in Figure 14, the piston has to carry over in instantaneous motion in order to come into the theoretical position, after 45 which it may again take up its loose lagging condition this time, however, in the opposite direction, because of the fact that the primary rotor now assumes a decelerative motion relatively to the secondary rotor. Obviously, this instantaneous position changing occasions great shock 50 and makes itself apparent in the form of noise and breakage.

55 Shortly summarizing the significance of Figure 16 it will be seen that during one half of a revolution of the pump assembly the secondary rotor is in accelerated motion relatively to the primary rotor, whereas during the other half of the rotation this relation changes, and the secondary rotor assumes a decelerated motion relatively to the primary rotor. The coupling 60 members of the assembly, that is the pistons, have to take up the rotary forces of one of the members if the other is in connection with a driving shaft, driven at uniform speed from a constant speed from a suitable source of power, say for example an electro-motor. It is evident from above 65 consideration that the synchronous rotation of the rotating pump members requires rigid connection between themselves, which positive coordination has been provided for in my present rigid 70 piston unit construction, which is capable of tak-

75 ing up the rotary accelerative forces between cylinder and eccentric eliminates the impacts caused in some structures of the prior art by free rocking of the crosshead relatively to its plunger, and thereby provides smoother running of the pump in addition to eliminating torsional oscillation of the coupled rotary members of the pump. The positive attachment afforded by my novel type of self-aligning piston and crosshead units makes it possible to transmit in tune and continuously 10 the synchronous forces from one rotor to the other especially in the change points, where the forces are zero.

From the distance relation $x = \rho \sin \phi$ of the center lines, it follows by the simple rule of mechanics, that the acceleration $x = \rho \omega^2 \sin \phi$ i. e. the acceleration is in direct proportion with the second power of the angular speed ω of the pump. The force produced by the impact is further proportional with the mass of the piston unit. The 20 larger the stroke, i. e. the greater the pump is, the greater will be the need for a synchronous coordination of the rotating members during their high speed rotation.

The many advantages afforded by my improved 25 piston and cross head units should be readily appreciable. Flexible connections, such as are shown in Figure 12 cause eccentric loading on the bottom of the hollow piston there shown, and the eccentric load results in a tangential component 30 of the hydraulic load, and causes wall friction and wear on cylinder wall. As long as the speed of the pump in proportion to the flexibility of the piston is negligible, and the eccentricity and stroke of the pump are small, the above-named 35 faults give little trouble at medium pressures. However, at higher pressures, the faults of eccentric piston load occasion serious troubles and in combined high speed and greater stroke designs are intolerable.

40 The application of flexible piston connections used in the prior art arises from the necessity to provide compensation for the deflection of pintle and distortion of secondary rotor. In order to illustrate this more clearly I have shown 45 in Figures 11, 12, and 13 three different units of properly related proportions and adaptable to use in pumps of like capacity of output. Figure 13 shows my novel integral rigid piston with self-aligning cross head unit.

50 Figure 11 shows another form of piston selected from a prior art pump of this type. This prior art piston is well known to include two slippers held in cooperative relation on a pin having a diameter d_2 . The pin naturally has to take all 55 of the hydraulic load of the piston and is of the crank type arrangement. This can not effect positive coupling between primary and secondary rotors, but permits the secondary rotor to float.

In Figure 12, there is shown another prior art 60 piston, in which the load is transmitted to the cross head by a push pin integral with the cross head and having a diameter d_3 .

By a glance at Figures 11, 12, and 13, it will become evident that each piston has a diameter 65 D , consequently each is able to suck the same amount of fluid during a given stroke. However, by reference to Figure 13, it will be seen that my load-transmitting capacity has the full diameter D , whereas the maximum possible pin diameter in 70 Figure 11 is about one half of D , and in addition is exposed to combined stresses. Thus it will be seen that the section modulus of the pin of Figure 11 is about one-eighth of the section modulus of that in Figure 13 and, therefore, its 75

load-carrying capacity is only one-eighth that of my plunger.

In Figure 12, the maximum possible diameter of the pin is only about one-third of that of the pin or section of Figure 13 which makes it only one-twenty-seventh as strong as the section modulus are in a proportion as the third power of the diameters.

Therefore, it should be obvious that my improved unit is able to carry twenty-seven times as much load with the same factor of safety as the unit of Figure 12 and three times as much as the unit of Figure 11.

In order to visualize the balanced condition of my improved pump while in motion, calling it dynamical balance, let us consider the secondary rotor or eccentric as indicated in Figure 15 with one of its pistons located in its groove without definite attachment in tangential direction. By considering the fact that the secondary rotor rotates around its concentric bearing at constant speed, it is evident that a piston unit with integral rigid plunger and cross head unit, as shown in Figure 15, will stay in its position of the center line of the rotor, without need of employing any forces other than centrifugal force caused by the rotation and denoted by R_2 in Figure 15.

In order that the pistons shall follow the rotation of the primary rotor or cylinder, as shown in Figure 13, and in order to impart a harmonic oscillation to the piston in the direction of the cross head groove, it is necessary that the primary rotor impart tangential forces T_1 and T_2 to the piston and thus attain the pure harmonic oscillation in the secondary rotor as illustrated in Figure 15. The tangential motion of the piston in the secondary rotor is therefore provided by the primary rotor, and according to the law of equilibrium, the tangential forces T_1 and T_2 will occasion equal but oppositely directed forces T_1 , T_2 on the shaft of primary rotation as reactions. In a similar manner the centrifugal forces awake reaction forces on the shaft of the secondary rotor. It is evident from above reasoning that the centrifugal forces of the rotary pistons are controlled by the secondary rotor and taken up by the bearing of it, whereas the tangential forces of the pistons are controlled by the shaft of the primary rotor.

In order to illustrate more clearly the above rules, in Figure 19, I have shown the primary rotor A, the center of primary rotation O_1 , the secondary rotor B, the center of secondary rotation O_2 , and seven piston units, all integral rigid pistons C serving as coupling means between primary and secondary rotors. Considering the secondary rotor to have an eccentricity ρ and a stroke 2ρ , a careful inspection of this illustration reveals that the distribution of the piston units in the grooves of the secondary rotor is not uniform, in regard to the axis N—N, also non-uniform around the axis O_2 . All pistons are kept in equally spaced angular relation around the primary axis O_1 , however, this does not follow in the radial directions so that it will be found desirable to consider the relations of pistons and the primary and secondary rotors separately as shown in Figures 17 and 18.

The effect of the rotary piston forces on the balance of the primary rotor will be evident by reference to Figure 17 wherein it will be seen that the rotary piston forces are greater toward the right of a vertical line intersecting the axis of rotation of the primary rotor.

The effect of rotary piston forces on the bal-

ance of the secondary rotor is shown in Figure 18. The rotary piston forces are over-balanced toward the left of a vertical line intersecting the axis of rotation of the secondary rotor. These drawings also show that the rotary forces are in balance in regard to the horizontal axis N—N in the primary as well as the secondary rotors. 5

It will be noticed that the over-crowding of the pistons in the one side of the secondary rotor will balance the over-stroking of the pistons in the other side as soon as the piston plunger and cross head are rigid and integral. As a result of many years of experience and study of this balance problem, I found out that the total increment of the accelerative forces of the eccentrically located pistons acting with the cylinder barrel in tangential direction will be equal to the total increments of the accelerative forces of the pistons in the eccentric when there is a positive and definite dynamical connection between cylinder barrel and eccentric and when there is a proper relation between the mass of the plunger and the mass of the cross head itself. In order to avoid shocks and mechanical oscillations between cylinder and eccentric, it is necessary at all times 25 that the rotary piston forces of harmonic oscillation in each of the rotors are equal and be imparted simultaneously to the relatively rotating members to create permanent balance between the co-rotating assembly. 30

I will attempt to illustrate further, by comparison how, in my improved pump structure, the combination of the new integral rigid pistons and their perfect alignment producing features assure dynamical balance at all times, thus eliminating torsional vibrations from the pump. Figure 14 illustrates that a flexible piston assembly such as is shown cannot transmit synchronous rotation of the primary and secondary rotors because of the time lag permitted by the looseness of the piston rod in its hollow piston. Therefore, the proper geometrical relation, shown in Figure 16, and wherein the pistons are first accelerated then simultaneously decelerated in the eccentric cannot be accomplished in such structures as shown in Fig. 14 and the simultaneous values are not equal, the rotating pistons themselves have no positive guide in their respective paths. As the positions of the pistons in such devices are flexible and determined only by limiting means in their respective members, it is obvious that the transmission of balancing dynamical forces between the rotors is not continuous but intermittent, i. e., shock-like and therefore it causes shocks and vibrations varying in violence according to the degree of looseness and free rocking of the rotating pistons. 55

In the case of use of loose and indefinite connections of rotating systems considerable wear on the pistons is produced by the dynamical forces which cannot be uniformly distributed on all of the pistons and those which are looser than others are not able to transmit their own share and consequently subject the remaining pistons to intolerable stresses. In my many years experience with such units I have witnessed much breakage attributable to these inefficiencies. Even with piston units as shown in Figure 11 wherein the pin is larger and has less play than the push pin shown in Figure 12, the enormous rotary forces, 70 or rather the forces of the harmonic oscillation of the cross heads, cause, in a very short time, oblique wear in two right angled directions as shown in Figure 11a, and thus soon produce loose wrist pins and indefinite rotor connection. In 75

pumps incorporating such pistons, dynamic balance can not be effected between the rotors due to the fact that the plunger rocks in regard to the cross head shoe. The seriousness of the existence of unbalanced forces cannot be over emphasized, as they increase in magnitude at a quadratic rate with the speed and their effect is cumulative and destructive.

Another advantage of my improved integral rigid piston unit structure resides in the greater suction effort efficiency occasioned by its use. The suction effort of my improved piston unit is much more steady and positive than in the case of resilient connections of the type shown in Figure 12. In addition the integral pistons have a flywheel effect and provide for a more steady and uniform rotation of the system, and at the same time improve the dynamical balance of the whole system.

In addition also to this flywheel effect and the provision of positive connection between the primary and secondary rotors the great weight of the piston and cross head units enable them to operate during the suction or outward strokes by centrifugal force alone acting on their masses thus permitting them to remain always in cushioned contact with the reaction face of the secondary rotor and avoiding the necessity of changing seats on inner and outer surfaces of the secondary rotor and the noise and shocks resulting from such seat changing.

Still another advantage of the steady dynamical balance for which I have provided resides in having the central valve or pintle forming the bearing for the primary rotor take up the balanced forces steadily instead of intermittently, thus insuring a steady and continuous oil film bearing.

From the foregoing description taken in connection with the accompanying drawings it is thought that the novel details of construction, the manner of use and the advantages of my invention will be readily apparent to those skilled in the art to which it relates.

I claim:

1. In a pump or motor, a primary rotor having a cylinder, a secondary rotor having a guideway, a piston reciprocable in said cylinder, and a two-part cross head located within said guideway and having one part rigidly attached to and movable with the piston, said cross head parts having mating cylindrical surfaces whose axis is parallel to the axis of rotation of one of said rotors.

2. In a pump or motor, primary and secondary rotors rotatable about separated axes, and radial

piston and cylinder assemblies connecting the rotors and including cross heads, the pistons being caused to reciprocate in said cylinders by reason of the movement of the rotors about their separated axes, one of said rotors being tangentially grooved to slidably receive said cross heads, and each said cross head being formed of two elements, one element being rigidly attached to its piston, said elements having correspondingly curved relatively-reciprocable cylindrical mating surfaces whose axis is parallel to the axis of rotation of one of said rotors. 5

3. In a pump or motor, primary and secondary rotors rotatable about separated axes, and radial piston and cylinder assemblies connecting the 15 rotors and including cross heads, the pistons being caused to reciprocate in said cylinders by reason of the movement of the rotors about their separated axes, one of said rotors being tangentially grooved to slidably receive said cross heads, 20 and each said cross head being formed of two elements, one element being rigidly attached to its piston, said elements having correspondingly curved relatively-reciprocable cylindrical mating surfaces, the curves of which are struck from a 25 common axis remote from the cross head, the axis of said mating cylindrical surfaces being parallel to the axis of rotation of one of said rotors.

4. In a pump or motor, a primary rotor having 30 a cylinder, a piston reciprocable therein, a secondary rotor having a guideway, a two-part piston crosshead located within said guideway and having mating cylindrical surfaces of the same curvature whose axis is parallel to the axis of rotation of one of said rotors, with the centers of curvature of said surfaces lying on the rotational axis of said primary rotor, one of said cross head parts being rigidly attached to said piston.

5. In a pump or motor, a primary rotor having 40 a cylinder, a piston reciprocable therein, a secondary rotor, a crosshead guide block secured to said secondary rotor and having a guideway therein, and a two-part piston crosshead located within said guideway and having mating cylindrically-curved surfaces providing free sliding contacts between said crosshead and said guideway, said crosshead guide block guideway being arranged for reciprocating movement of the two-part piston crosshead relatively thereto, the axis 45 of said mating cylindrical surfaces being parallel to the axis of rotation of one of said rotors, one of said crosshead parts being rigidly attached to said piston.

ELEK K. BENEDEK. 55
